UNITED STATES PATENT OFFICE.

WILLIAM GADKE, OF PHILADELPHIA, PENNSYLVANIA.

ELECTRICAL COUPLING.

1,276,340.

Specification of Letters Patent. Patented Aug. 20, 1918.

Application filed September 2, 1915. Serial No. 48,677.

To all whom it may concern:

Be it known that I, WILLIAM GADKE, a citizen of the United States, residing in Philadelphia, Pennsylvania, have invented 5 certain improvements in Electrical Couplings, of which the following is a specification.

One object of my invention is to provide novel means for electrically connecting a 10 conductor such as an insulated wire, to a terminal; the invention more particularly contemplating a device for connecting the terminals of a timer for an internal combustion engine, with the several cables leading 15 therefrom to the spark coil and spark plugs.

It is also desired to provide a timer with a connection for detachably holding a cable to a terminal, the parts being so arranged that while they may be quickly assembled 20 or separated, their accidental separation shall be rendered unlikely.

These objects and other advantageous ends I secure as hereinafter set forth, reference being had to the accompanying drawings, in 25 which—

Figure 1 is a vertical section on an enlarged scale illustrating the detail construction of a connecting device constructed according to my invention;

30 Figs. 2 and 3 are elevations at right angles to each other showing my connecting device as applied to an insulated conductor;

Fig. 4 is a development of the contact cap shown in Figs. 2 and 3, and

35 Fig. 5 is a modified form of the terminal post and coupling sleeve associated therewith.

In order to connect the various conductor cables of an ignition or other current distributing system to terminals and at the same time effectually cover and insulate the joints, I provide for each of them a hollow cylinder 18 of insulating material closed at one end and having in its side adjacent 40 said end an opening formed to receive and closely fit a terminal 10 in the form of a metallic post having an annular shouldered depression forming a neck 13 adjacent its head 14. The outer end of this opening is 45 preferably counter-sunk so that it closely fits the convex top of an insulating bushing 16 in which the terminal is mounted. The 50 cable or conductor 20 to be attached to the

terminal consists of a stranded conductor 19 surrounded by a body of insulating material, and in order to insure good electrical contact between this conductor and the metal of the terminal I provide a second terminal in the form of a cap of sheet metal, usually brass or copper, which when developed preferably has the form shown in Fig. 4. Said metal cap 21 is shown as made up of a substantially rectangular body from one of whose long sides projects a long tongue 22 and a short tongue 23, and of these, the latter has a perforation 24 adjacent its outer end. In order to utilize this strip it is rolled into approximately cylindrical form as shown in Figs. 2 and 3, with its long tongue 22 bent inwardly toward its axis and then 60 substantially at right angles so as to extend outwardly.

The body adjacent the long tongue 22 is provided with a pressed-out projection 25 and in applying it to the end of the conductor, it is slipped over the insulation on the end of the same with the stranded conductor 19 passed through the opening 24 in the short tongue 23, after said tongue has been bent at right angles over the open 70 end of the cylindrical body. Said conductor is then wrapped around the long tongue 22 adjacent the sharp bend thereof so that it forms a small compact coil in line with the end of the rolled up body portion within 75 the lines of the sides thereof. The projecting portion or lug 25 extends outwardly from the lower end of the body and is designed to enter and coact with the walls of an annular groove 26 formed adjacent 80 one end of a metal sleeve 27 frictionally held within the insulating cover 18, which sleeve as shown in Fig. 1, has openings in line with each other adjacent its inner end 85 for the reception of the terminal 10.

With the above described arrangement of parts, the insulating cover 18 is applied to the terminal 10 which extends into it through its side openings. Thereafter the secondary terminal formed by the rolled up 90 metal piece 21 is applied to the end of a cable as shown in Figs. 2 and 3, and is inserted within the sleeve 27 of said cover cylinder 18, with its more or less springy tongue 22 in position to present one of its 95 flat faces to the cylindrically recessed por-

tion or neck 13 of the terminal, while the projection 25 enters the annular groove 26 of said sleeve; it being noted that in forming the body of the secondary terminal 21 it is loosely fitted to the insulation of the cable so as to be more or less contractile.

When the second terminal has been thus engaged with the sleeve of the cover 18, its long tongue 22 strikes and is slightly forced outward by the neck 13 of the terminal 10, forming a good electrical contact and effectually preventing removal of said cover from the terminal, since its edge engages the shoulder between the head 14 and neck 13, and the parts are effectually locked together. At the same time the cover with the cable 20 is free to rotate on the terminal in a plane at right angles to the line thereof without disturbing its electrical engagement with said terminal and without the possibility of accidental disconnection or separation of the parts.

If for any purpose it should be desired to remove the cable from the terminal, it may be forcibly drawn out of the sleeve 27 in the cover 18, thus drawing the spring tongue 22 from engagement with the neck 13 and permitting the cover to be raised off of the same.

30 As shown in Fig. 5, the terminal post, instead of being provided with a head and neck, may be threaded at its outer end as indicated at 30, in which case the metal sleeve 27^a within the insulating sleeve 18^a is of the construction shown in Figs. 2 and 3 except that the spring tongue 22^a is materially shorter, having as before the end 19 of the conductor 20^a wound around it. It is noted that the insulating material in which the terminal post is mounted has a convex form surrounding the same and is designed to fit into a correspondingly formed recess of the insulating sleeve so as to make a substantially weather-proof joint therewith.

50 I claim;—

1. The combination of a terminal having a neck of reduced diameter; an insulating sleeve fitting over said terminal; with a conductor removably fitting said sleeve and having a tongue of flat spring material arranged with its flat surface engaging the curved surface of the neck of the terminal, said tongue coacting with the shoulder at one end of said neck to lock said parts together.

2. The combination of a terminal; a sleeve of insulating material; an insulated conductor; a metal sleeve yieldingly surrounding the insulation adjacent one end of the conductor and electrically connected to the

latter; said sleeve including a tongue extending into locking engagement with the terminal; and a projection-and-recess connection for separably retaining said metallic sleeve within the insulating sleeve.

70

3. The combination of a conductor; a body of insulation surrounding the same; a split metal sleeve yieldingly mounted adjacent the extremity of said insulation and having a projecting contact portion in electrical connection with the conductor; a sleeve; and a recess-and-projection connection between the split sleeve and the latter sleeve.

4. The combination of a conductor; a split metal sleeve yieldingly mounted thereon and having a projection; a non-yielding metal sleeve formed to fit over the split sleeve and provided with an annular recess for the reception of the projection thereof; with an insulating sleeve inclosing and in intimate permanent contact with said second sleeve.

5. The combination of a terminal in the form of a post; an insulating sleeve; a metal sleeve mounted in said first sleeve, said sleeves having side openings in line with each other for the reception of said terminal post; with a conductor removably fitting said metal sleeve and having locking engagement with the terminal post.

95

6. The combination of a fixed body of insulating material having a convex portion; a terminal post extending therethrough; an insulating sleeve having a concave recess for the reception of the convex portion of said body of insulating material and provided with an opening for the terminal post; with means for temporarily locking the terminal post in said sleeve.

10

7. The combination of a fixed body of insulating material having a convex portion; a terminal post extending therethrough; an insulating sleeve having a concave recess for the reception of the convex portion of the fixed body and provided with an opening for the terminal post; with means for temporarily locking the terminal post in said sleeve, the same consisting of a conductor removably fitting into the sleeve and having a contact portion electrically engaging said post.

11

8. The combination of a body of insulating material having a convex portion; a terminal post extending therethrough; a metallic sleeve engaging said terminal post; with a body of insulating material surrounding said sleeve and provided with a recess for the reception of the convex portion of the body of insulating material.

1

9. The combination of a body of insulating material having a convex portion; a terminal post extending therethrough; a metallic sleeve engaging said terminal post; a body of insulating material surrounding said sleeve and provided with a recess for

65

the reception of the convex portion of the body of insulating material; with a conductor removably fitting the sleeve and having a separable projection-and-recess connection therewith.

10. The combination of a conductor; a body of insulating material thereon; a longitudinally split contractile metal sleeve

mounted on said body and having at least two projections; with a second sleeve formed to receive the split sleeve and provided with a recess for the reception of one of said projections, the other projection being in electrical engagement with the conductor.
